DRINK DISPENSING MACHINE

James Howard McLellan, Vancouver, British Columbia, Canada

Application January 24, 1934, Serial No. 708,074

9 Claims. (Cl. 225—21)

My invention relates to improvements in drink dispensing machines, the objects of which are to provide means for moving a cup under a filling spout for dispensing thereinto a measured quantity of liquid and for disposing said cup after filling in a position accessible to the purchaser. Other objects are to provide a mechanism which is positive in its action and is not dependent on springs to carry a part through one stroke of its movement, and a still further object is to provide means for returning a coin entered into the coin lock, to the purchaser, if a cup is not in position to be filled, as will be more fully described in the following specification and shown in the accompanying drawings, in which:—

Fig. 1 is a front view of the invention.

Fig. 2 is a plan view with the cup carrier removed.

Fig. 3 is a plan view of the cup arm and door operating movement.

Fig. 4 is a plan view of the cup carrier rotating means.

Figs. 5, 6, 7 and 8 are diagrammatic views of the cup arm swing, valve, door and cup arm drop operating movements respectively, the cams of these movements all being shown in the same relative position.

Fig. 9 is a plan view of the main switch controls.

Fig. 10 is an elevational view of same.

Fig. 11 is an elevational view of the coin controlled switch.

Fig. 12 is a wiring diagram.

Fig. 13 is an end view of the invention.

In the drawings like characters of reference indicate corresponding parts in each figure.

The numeral 1 indicates a base supporting a motor 2 which imparts rotation through a worm and worm wheel 3 to a horizontal shaft 4, the drive from this latter shaft is communicated through a worm and worm wheel 5 to a shaft 6 upon which a sleeve 7 is journaled. The sleeve 7 is fitted at one end with a worm 8 and at the other with a clutch plate 9 forming part of a clutch 10. Slidably mounted and suitably keyed to the shaft 6 is a collar 11 having at one end a clutch plate 12 also forming part of the clutch 10. Carried in suitable bearings from the base is a vertical cam shaft 13 which is driven through a worm wheel 14 from the worm 8.

Mounted upon an elevated horizontal plate 15 is a cup carrier 16 which consists of a vertical spindle 17 carrying a spider 18 which supports a plurality of columns of nested cups 19 and is adapted to drop one cup at each predetermined interval of rotation of the spindle 17.

At the upper extremity of the cam shaft 13 is a crank 20, see Figures 1 and 4. On the base of the spindle 17 a ratchet wheel 21 is secured, and rockingly mounted upon the spindle adjacent the wheel 21 is a lever 22 carrying a spring pressed pawl 23, the free end of the lever is connected by a rod 24 to the crank 20, so that at each rotation of the cam shaft 13 the cup carrier is turned to drop a cup into a cup arm to be hereinafter described.

Fitted upon the cam shaft 13 are four cams respectively indicated by the numerals 25, 26, 27 and 28. While some of the cams are shown as face cams for the purpose of simplicity, it will be obvious that they may be provided with cam paths so as to impart both forward and return motion to their several associated levers and parts.

The path of the cam 25 is divided into segments A, B, C and D, that of cam 26 into segments E and F, that of cam 27 into segments G and H, and that of cam 28 into segments I and J, the purpose of which will be apparent in the description of the cycle of operations of the machine.

Slidably mounted in vertical bearings 29 and 30 is a grooved shaft 31 which engages intermediate its length, a toothed quadrant 32. Secured to the shaft is a boss 33 from which a cup arm 34 extends. A key 35 is fitted in the quadrant which engages the groove of the shaft 31 so that the rocking of the shaft will impart a swinging movement to the cup arm.

A bell crank 36 is journaled upon a shaft 37 and is provided at one end with a roller 38 engaging the path of the cam 25 and at its opposite end a gear segment 39 which meshes with the quadrant 32, so that the rotation of said cam will impart a reciprocal swinging movement to the cup arm 34.

The cam 26, see Figure 8, engages a roller 40 on a lever 41 which carries at its fulcrum a segment of a bevel pinion 42, this pinion engages a similar bevel gear 43 which raises and lowers a horizontally mounted lever 44, the free end of which engages the lower end of the shaft 31 of the cup arm, so that simultaneously the cup arm is raised and lowered.

Above the path of a cup carried by the cup arm 34 is a valve 45 shown in dotted line in Figure 1 and in full line in Figures 2 and 6, which communicate with a measured source of liquid supply through a port 46 and is provided with a discharge outlet 47. The valve is fitted with a plunger 48 and a rod 49 which are urged outwards or to close, by a compression spring 50.

Mounted on a vertical shaft 51 is a lever 52, see

Figure 6, which is provided intermediate its length with a roller 53 engaging the path of the cam 28. The free end of the lever 52 is connected by a rod 54 to a lever 55 which is secured 5 to a vertical shaft 56 to which is also secured an arm 57 the free end of which engages the plunger rod 49 to thrust it inwardly in response to the rotation of the cam 28, and to so dispose the plunger 48 as to provide communication between the port 46 and the discharge outlet 47 to permit the discharge of the measured quantity of liquid into the cup 19 supported below said discharge outlet.

Secured to the shaft 56 is a short crank 58 which is connected to a push rod 59, the purpose of which will hereinafter appear. Also mounted upon the shaft 51 is a lever 60 having a roller 61 intermediate its length which engages the path of the cam 27. The free end of this lever is connected by a rod 62 to a quadrant 63 shown in dotted line in Figure 7 which carries an arcuate door 64. The quadrant 63 is pivoted below a delivery shelf 65 which preferably extends inwardly from the outer covering of the machine and is surmounted by side walls 66 and a top wall, not shown, so as to form a delivery recess 67 and provide access to the delivered cup from the outside of the machine.

As a means for preventing damage to the machine through malicious entry of an obstruction to the closing of the door to the delivery recess the connecting rod 62 is made telescopic and a spring is provided to maintain it normally in extended form.

The cup arm 34 is provided at its free end with a C-shaped collar 68 between the ends of which a gap 69 is defined, and below this, mounted upon a horizontal shaft 70, see Figures 1 and 2, is a cup receiving tray 71 having a counterweight 72 sufficient to slightly raise the tray above the horizontal position when no cup is in the collar 68 and to be lowered to horizontal position when a cup is in said collar. Secured to one end of the shaft 70 is a crank 73 which is connected by a rod 74 to a swingingly mounted section of coin tube 75.

A coin chute 76 having ducts 77 and 78 is provided which communicates with a coin receiver below the machine, not shown, and a coin return recess 79 which is accessible from the exterior of the machine. The duct 78 leads downwardly directly from the coin lock to the recess 79 and is adapted to return slugs or defective coins, the duct 77 is adapted to convey coins from the coin lock to the coin receiver, after passing through the coin tube 75, or, if the tube is inclined as shown in dotted line in Figure 1, due to the absence of a cup upon the tray 71, the coin is transferred from the duct 77 to the duct 78 and is dropped into the recess 79 for return to the would be purchaser. Normally projecting into the duct 77 is a trigger 80, see Figure 11, the upper end of which forms a latch 81 which slidably engages a spring tensioned rocker arm 82 of a switch 83. The rocker arm is slightly indented on the underside as at 84 to hold the latch in the position shown until the trigger is moved by the weight of a coin passing through the duct 77, and it is also provided with a stop 85 at its outer end to limit the opposite movement of said trigger to that shown in dotted line. The trigger when displaced by a coin enables the rocker arm 82 to be swung by its spring to close the switch 83.

Mounted parallel to the shaft 6 is a solenoid

86, see Figures 1, 2, 9, 10, 11 and 12, connected in a circuit "X" from the power supply in which is included the switch 83 and a further switch 87. The armature of the solenoid is connected to a rod 88 having a fork 89 at one end which engages the collar 11 to engage the clutch 10 and having a transverse pin 90 shown in dotted line in Figure 9. Engaging the pin 90 is the forked end of a bell crank 91, the opposite end of which is adapted to be engaged by a spring 10 tensioned trigger 92 having a limited throw and is carried upon a disc 93 mounted upon the cam shaft 13, so that at each complete revolution of said shaft and its cams 25, 26, 27 and 28 the armature of the solenoid is withdrawn to disengage the clutch 10. Integral with the bell crank 91 is an arm 94 having an insulated finger 95 which when the machine is at rest holds the contact points of a switch 96 open. This switch is included in a circuit Y controlling the motor 20 2 and is placed close to the switch 87, so that as the solenoid 86 is energized and the bell crank 91 rocked to swing the arm 94 into the position shown in dotted line, the insulated finger will move to allow the switch 96 to close and start the motor and to open the switch 87 to open the solenoid circuit "X". In order to prevent accidental movement of the armature and the rod 88 when the solenoid circuit X is open, a pin 97 extends from the arm 94 which slides past 30 a projection 98 on a spring tensioned latch lever 99.

When a coin has passed through the coin lock and entered the duct 77 it passes through the swinging coin tube 75, provided a cup is at rest 35 upon the tray 71, and strikes the trigger 80, forcing it outwards from the duct and allowing the rocker arm 82 to swing and close the switch 83, the switch 87 being then closed in the solenoid circuit X, the solenoid 86 is energized, drawing 40 its armature and the rod 88 endwise to engage the clutch 10 and to swing the arm 94 to close the switch 96 in the motor circuit Y and then to open the circuit X so that the current ceases to flow through the solenoid. The free end of 45 the bell crank 91 is by this movement moved into the path of the spring tensioned trigger 92, which starts to move in response to the operation of the motor.

The several cams during their rotation perform the following functions through their associated parts:—Cam 25 in moving through the arc A moves a cup, previously dropped into the collar 68 of the cup arm 34, under the discharge of the valve 45. The cam 28 in passing from the 55 arcs J to I opens the valve to discharge a given quantity of liquid into the cup. Subsequent to these two movements, a pause takes place in the cup arm swing during the travel of the arc B of cam 25 in contact with the roller, while the 60 valve remains open to fill the cup. The roller engaging cam 28 in passing from the arcs I to J closes the valve and the cam 27 in passing from the arcs G to H opens the door 64 at the rear 65 of the delivery recess and the roller engaging the cam 25 traverses the arc C, thus swinging the cup arm to move the cup into the recess 67, no further movement of the cup arm takes place until the roller engaging cam 26 starts to enter 70 the arc F, thereby causing a lowering of the cup arm to dispose the gap 69 of the cup collar at a point of lesser diameter of the cup when the return movement of the arm due to the roller engaging the arc D of cam 25 will remove said 75

collar from the cup leaving the latter standing in the recess. As soon as the cup arm collar is removed from the recess, the roller engaging cam 26 starts to move outward from along the arc F, 5 thus restoring the cup arm to its raised position while it is still returning to its normal position of rest, and simultaneously, while the roller is passing from the arcs H to G on cam 27 the door is drawn to closed position. Simultaneously 10 with the opening of the valve by the cam 28 the rod 55 is moved rearwardly to swing the trigger, to project into the duct 77 and to swing the rocker arm 82 to close the switch 83.

The final movement in the rotation of the cam 15 shaft 13 causes the spring tensioned trigger 82 to rock the bell crank 81, thus swinging the arm 94 to close the switch 87 in the solenoid circuit X and open the switch 88 in the motor circuit Y.

The rocking of the bell crank 81 also imparts 20 endwise movement to the rod 88 to open the clutch 10, so that the momentum of the motor may be dissipated without imparting any movement to the cam shaft 13 or any of its associated parts. Just as the cam shaft 13 comes to rest the crank 25 20 will be disposed in the position shown, so that a further cup will be released from the cup carrier 16 and allowed to drop into the collar 68 of the cup arm ready for the cycle of operations to be completed.

When the machine is in operation and a cup 30 has been carried beyond the end of the tray 71 in its passage to filling and delivery positions, the tray swings upwards, thus through the rod 74 swinging the deflecting section of the coin 35 tube 75 into operative or inclined position, so that in the event of another person depositing a coin into the machine before the filled cup is delivered and the cup arm returned to starting point, the said coin will pass through the duct 40 77, thence through the deflector into the duct 78 and thence into the coin recess 79.

What I claim as my invention is:

1. In a drink dispenser having a valve, a cup 45 feeding means and a cup delivery shelf, a radially movable cup carrying arm adapted to receive a cup from the feeding means, means for moving the arm to dispose the cup to be filled by the valve, for holding the cup at rest during filling and to move said cup after filling to the delivery 50 shelf and for returning said arm to cup receiving position, and means for releasing the cup.

2. In a drink dispenser having a valve, a cup 55 feeding means and a cup delivery shelf, a radially movable cup carrying arm adapted to receive a cup from the feeding means, means for moving the arm to dispose the cup to be filled by the valve, for holding the cup at rest during filling and to move said cup after filling to the delivery 60 shelf, for returning said arm to cup receiving position, and means for lowering the arm when at delivery position for releasing the filled cup.

3. In a drink dispenser having a valve, a cup 65 feeding means and a cup delivery shelf, a radially movable cup carrying arm adapted to receive a cup from the feeding means, a cam for moving the arm to dispose the cup to be filled by the valve, for holding the cup at rest during filling, to move said cup after filling to the delivery shelf

and for returning said arm to cup receiving position.

4. In a drink dispenser having a valve, a cup feeding means, a cup delivery shelf and means for receiving a cup from the feeding means for moving it into filling position adjacent the valve and for depositing said cup after filling into the cup delivery shelf, a motor, a solenoid for connecting the motor to drive the cup receiving, filling and delivery means, a circuit for the sole- 10 noid, a switch within the circuit and means preventing access to the switch.

5. In a drink dispenser, a valve, a cup feeding means, a cup delivery shelf, and means for receiving a cup from the feeding means for mov- 15 ing it into filling position adjacent the valve and for depositing said cup after filling into the cup delivery, a motor for driving the cup moving means, a solenoid, and a circuit therefor, a clutch for communicating and disrupting said drive, 20 said clutch being engageable in response to the energizing of the solenoid, a switch for closing the solenoid circuit, and mechanical means actuated by the cup moving means for withdrawing the armature of the solenoid to disconnect the 25 clutch.

6. In a drink dispenser adapted to be mechanically driven and coin operated and having a cup 30 arm for receiving a cup and passing it through a delivery opening after filling, a motor, a driven shaft and a clutch between the motor and the shaft, a solenoid for engaging the clutch, a rotatably mounted trigger carried by the shaft, a means interposed between the path of said trigger and the clutch for disengaging the clutch 35 and withdrawing the armature of the solenoid on the engagement of said means by said trigger.

7. In a drink dispenser having a driven shaft, a cup arm mounted upon a vertical shaft, said cup arm being adapted to receive a cup and to 40 move said cup to a point of delivery, a valve for filling the cup, means engaging the cup arm shaft for lowering and for disengaging the cup arm from the filled cup and a cam upon the shaft for moving the cup arm, first to a position below 45 the valve, thence to the point of delivery, one for operating the valve and one for operating the cup arm shaft lowering means.

8. In a drink dispenser having a driven shaft, a delivery opening and a door for closing said 50 opening, a cup arm adapted to receive a cup and to pass it through said opening, a valve for filling the cup, means for disengaging the cup arm from the filled cup, and a cam upon the shaft for moving the cup arm, one for operating the 55 valve, one for operating the door and one for operating the cup disengaging means.

9. In a drink dispenser having a cup arm mounted upon a vertical shaft, said cup arm being adapted to receive a cup and move it to 60 a point of delivery, means for lowering and raising the shaft and the cup arm, an element in each of said moving means for rendering the movements of the cup arm from cup receiving position to point of delivery and return, and the 65 lowering and raising of the cup arm and its shaft positive throughout their cycles.

JAMES HOWARD MCLELLAN.
